W. C. CUTLER

MACHINE FOR STORING AND SELECTIVELY DISPENSING ARTICLES

Filed Sept. 16, 1925

UNITED STATES PATENT OFFICE.

WILLIAM C. CUTLER, OF GLENDALE, CALIFORNIA, ASSIGNOR TO ISABELLA M. CUTLER,
OF GLENDALE, CALIFORNIA.

MACHINE FOR STORING AND SELECTIVELY DISPENSING ARTICLES.

Application filed September 16, 1925. Serial No. 56,708.

The present invention relates to selective vending machines and has for its principal object the provision of a comparatively simple and compact machine adapted to contain and vend a plurality of articles, any one of which may be obtained by a customer.

The invention is applicable to any machine, either manual or coin controlled, in which it is desired to store a plurality of individual articles so that any selected one of the articles may be had by proper operation of the machine, and it is another object of my invention to provide for properly housing and protecting each article while it is in the said machine.

Another object of the invention is to improve upon the machine set forth in my co-pending application, Serial No. 48,274, by doing away with the delivery chute, so as to reduce the amount of space occupied thereby.

Another object of the invention is to provide for easy replenishing of the machine.

Still another object of the invention is to provide a selective vending machine embodying a plurality of individual article holders, in which machine any article holder may be refilled without disturbing other article holders.

A further object of the invention is to provide a selective vending machine embodying a plurality of article holders and a single operating means for all the holders, in which machine an article may be obtained without moving or disturbing any of the other article holders and without moving the contents of such other holders.

Other objects and advantages of my invention will appear hereinafter and will be better understood because of the order in which they occur.

I have illustrated my invention by the accompanying drawings in which:

Figure 1 is a view in front elevation of one embodiment of my invention. Figure 2 is a view in section thereof on a larger scale, seen on a line 2-2 of Figure 1. Figure 3 is a view in section seen on a line 3-3 of Figure 2. Figure 4 is a plan view of the left hand end of the machine; and Figure 5 is a view in section, on the same scale as Figures 1 and 4, said view being seen on a line 5-5 of Figure 2.

More specifically, in carrying out my in-

vention, I provide a casing 8 embodying a front wall 9, a bottom wall 10, and an arcuate wall 11 connecting the bottom wall and top wall, directly or otherwise, to enclose parts about to be described. Within the interior of the casing I provide a plurality of revoluble or oscillatable article holders such as 12, all arranged in juxtaposition in a horizontal series. The machine shown is of the horizontal type but, obviously, it may be vertical, in which case the holders would be arranged one above the other in coaxial arrangement.

Any suitable means for oscillatably mounting the holders may be provided, but in the present embodiment I provide for each holder a U-shape yoke 14. Each holder includes spaced side walls 15 and each contiguous part of the supporting yoke is provided with a pivot pin 16 whereby each wall is pivoted to the corresponding yoke. It will be apparent now that an article holder so supported within the casing may be moved from the position in which it is shown in Figure 2 to the dotted line position independently of all other article holders. An inner wall 17 of each holder defines a rectangular space 18 adapted to contain an article, package, or the like, such as a box 19 in which may be contained a sandwich or any other article.

Each article holder includes a circumferential wall 18 co-axially described around its center of rotation and the center of the rectangular space is preferably the same as the said center of oscillation. The coaxial wall is cut away as at 20; or, in other words, the article holding space opens circumferentially of the holder for the removal or insertion of the article to be vended. The yokes which support the article holders are each shown as secured to the front wall of the casing, which wall may be a separate member to facilitate assembly, repair, or inspection of the machine.

The arcuate wall of the casing is described coaxially of the center of oscillation of the article holders and said wall is provided with an elongated rear opening 21 with which the opening of any article holder will register when the holder is moved to the dotted line position. While it is not essential, it is, however, helpful to provide each holder with a small coil spring 22 arranged to tend to move the contained article out-

wardly. Said spring accordingly causes a contained package or box to bear slightly on the inner surface of the arcuate wall. The arcuate wall, or an upper portion at least, is 5 hinged to the front wall as at 24 so that it may be raised to permit access to all article holders. The holders may be replenished by so doing, but it will appear hereinafter that a holder may be replenished independently 10 of the others without opening up the casing in any way.

For each holder there is provided a circumferentially disposed long coil spring or other elastic member 26, for the purpose of 15 urging the holder from the position in which it is shown in Figure 2 to the dotted line position. Accordingly, said spring is attached at one of its ends to the holder at 27, the other end being secured to the casing 20 as at 28. The circumferential wall of the holder is provided with a stop or pin 30 adapted to abut a latch 31. With the stop in abutment with the latch as shown the holder cannot be moved. The exposed part 25 32 of the circumferential wall, where it is accessible through the opening, is devoid of any means whereby it can be manually or otherwise moved, and if any unauthorized means were devised for moving it in either 30 direction the stop would prevent it from being moved to bring the open part of the holder into registration with the opening in the casing. Thus, while a portion of each article holder is actually exposed through 35 the opening in the casing, the contents of that holder are inaccessible except by proper operation of the machine. There is provided a latch 33 for each holder, all being strung on a single transverse shaft 33^a, which 40 may serve as a tie rod for the machine. The latches each include a projecting arm 34. By moving the outer end of an arm upwardly, the latch will be moved away from the stop on the corresponding holder and the said 45 holder will be moved by its spring until its stop strikes the stop 35, carried by the casing wall.

A latch releasing member 36 is provided 50 which is slidable along a transverse shaft 37 into registration with any selected latch. Said member is loosely engaged by the bifurcated end 38 of a rod 39 which is slidable along a shaft 40. Said rod extends through a slot 41 in the front of the casing and terminates in a handle 42. The front wall of 55 the casing is provided with sight openings 43 through which a portion of the circumferential wall of each holder may be seen and each holder may be provided with a 60 sight opening 44 whereby a portion of the contents of such holder is visible externally of the machine.

The shaft on which the latch releases is 65 slidably mounted is provided with a slot 45 in which rides a pin 46 carried by the latch

release. Thus the release may be moved slidably along the rock shaft, but when said shaft is rocked said release will rock with it. The release has an abutment surface 47 arranged to strike a registered latch and so 70 move it to release the corresponding holder. It will be understood that the rock shaft is driven or rocked by a handle 48 which is mounted externally of the casing. If the machine is to be used for manual operation, 75 the handle is directly connected to the rock shaft. If the machine is to be coin controlled, then suitable coin controlled means (not shown) may be provided at the point indicated by 49 to render the handle normally inoperative to move the latch release until the requisite coin has been fed to the machine as through a coin slot such as 46.

When the machine is empty, all holders will be so disposed that their circumferential openings are registered with the rear casing opening. Each holder is filled by inserting the article and by rocking said holder to bring the pin in locking abutment with the latch. Another way to fill the machine is 90 to raise the hinged arcuate top wall, move all the holders back to locked position, and then insert an article in each holder. When it is desired to obtain an article from the machine, the selecting handle is moved along 95 the front of the machine until it is approximately registered with the desired article, which latter is apparent through the opening.

With the selecting handle in such position, the latch release will be aligned with the 100 latch which holds the corresponding article holder in place. Now the rock shaft is rocked to cause the latch release to raise the adjacent end of the latch. With the latch now moved away from the pin the article 105 holder will be turned one-quarter revolution by the elastic member. Thus the circumferential opening of the article holder is brought into registration with the rear casing opening. Centrifugal force alone may 110 act to move the article slightly forward through the opening, or the package may be readily reached by having thumb holes (not shown) in the spaced side walls of the holder. In this embodiment, however, the 115 spring behind the article will eject it slightly so that it protrudes sufficiently to be reached at the rear of the casing.

It will be apparent now that I have provided a simple selective vending or dispensing machine in which all articles are housed against removal except by proper or authorized operation of the machine, and it will also be apparent that the machine may be devoid of discharge chutes, baffles and the like such as are ordinarily required to keep the articles out of reach, and, while I have shown and described a specific embodiment of my invention, I do not limit myself to any specific construction or ar- 125 130

angement of parts and may alter same as I desire or as occasion requires without enlarging the scope of my invention, within the appended claims.

5 Having described my invention, what I claim as new and patentable is:

1. In a selective vending machine, an article holder embodying a hollow cylindrical member provided with a circumferential wall; a portion of said wall being cut away to provide an outwardly opening article holding pocket in said holder, a casing embodying walls enclosing said holder, one of the walls being provided with an opening 15 having upper and lower margins respectively, disposed in close proximity to the circumferential wall; said holder supported revolvably in said casing co-axially of its circumferential wall and being movable on 20 such axis to dispose the cut-away portion of the circumferential wall of the holder out of registration with the opening; whereby the article holding pocket is inaccessible from points exterior to the casing when the 25 pocket is so disposed; said holder further movable on its axis to dispose the cut-away portion of the wall in registration with the pocket; said margins of the opening, and said circumferential wall coacting when the 30 holder is in the first mentioned position, to render the pocket inaccessible.
2. In a machine of the class described, a casing provided with an opening, a plurality of article holders in said casing, each 35 provided with an opening through which its contents may be moved, each holder being movable independently of the others to bring its opening into registration with the opening in the casing, a spring for each 40 holder normally tending to move the corresponding holder so that its opening is in registration with the opening in the casing, a latch for each holder adapted to hold such holder against movement by said spring,
- 45 each latch movable to release the corresponding article holder, a rock shaft paralleling the latches, and a latch raising member mounted on said rock shaft so as to be slideable thereon while turning therewith.
- 50 3. In a machine of the class described, a plurality of revolvably mounted article holders arranged in a series, each holder having an opening through which its contents may be moved, a casing having an opening co-extensive of the series of holders; each 55 holder movable on its axis independently

of the other to bring the opening of the moved holder into such position as to be in registration with the opening in the casing, and further movable to a position to 60 render its opening inaccessible through said casing opening, means for each holder locking same in such position that its opening is inaccessible through the casing opening, 65 means for each holder urging same to position where its opening is registered with the casing opening, and means operable externally of the casing for selectively releasing the locking means.

4. In a machine of the class described, a 70 plurality of disc-like article holders each oscillatable on its transverse axis, and each holder provided with a circumferentially opening pocket, intersecting a portion of the circumference, the holders all arranged 75 with their axes in line, a casing enclosing said holders to render the said portion of the circumference of each holder inaccessible when the holders are each in certain position, means for holding said holders in such 80 position; said casing provided with an opening coextensive of the article holders, and means operable externally of the casing to move any selected one of the holders on its axis so that said portion of its circumference is aligned with the opening in the 85 casing.

5. In a machine of the class described, a plurality of disc-like article holders each oscillatable on its transverse axis, and each 90 holder provided with a circumferentially opening pocket, intersecting a portion of the circumference, the holders all arranged with their axes in line, a casing enclosing said holders to render the said portion of 95 the circumference of each holder inaccessible when the holders are each in certain position, means for holding said holders in such position; said casing provided with an opening coextensive of the article holders, and means operable externally of the 100 casing to move any selected one of the holders on its axis so that said portion of its circumference is aligned with the opening in the casing, and a spring in each holder 105 tending to urge the contents outwardly, a portion of the casing being arcuately disposed to hold the contents of the holders against the urge of the spring.

In testimony whereof I affix my signature.

WILLIAM C. CUTLER.
